UNITED STATES PATENT OFFICE.

GEORGE S. MAXWELL, OF NEWARK, NEW JERSEY, ASSIGNOR, BY DIRECT AND MESNE ASSIGNMENTS, TO THE TAXIMETER REGISTER COMPANY, OF WASHINGTON, DISTRICT OF COLUMBIA, A CORPORATION OF DELAWARE.

TAXIMETER.

1,271,920.

Specification of Letters Patent.

Patented July 9, 1918.

Application filed June 16, 1911. Serial No. 633,457.

To all whom it may concern:

Be it known that I, GEORGE S. MAXWELL, a citizen of the United States, residing at Newark, in the county of Essex and State 5 of New Jersey, have invented certain new and useful Improvements in Taximeters, of which the following is a specification.

My invention relates to an improvement in taximeters.

10 The object of the invention is to provide a taximeter which will fully meet all the conditions which arise in service and which will furnish a permanent record of all details necessary for the owner of a vehicle 15 to know in order to keep control of the driver.

My invention will best be understood from a detailed description of the present preferred embodiment of the same, which will 20 now be described in connection with the accompanying drawings:

In the drawings:

Figure 1 is a front elevation of the apparatus with the casing and some of the 25 parts removed;

Fig. 2 a left-hand side elevation of the apparatus, the casing being removed;

Fig. 3 a similar view of the right hand side of the apparatus with the casing removed;

Fig. 4 a top plan view of the apparatus;

Fig. 5 a bottom plan view of the same;

Fig. 6 a front view of the exterior of the complete apparatus;

35 Fig. 7 a side elevation of the same;

Fig. 8 a top plan view of the same;

Fig. 9 a detail view of one corner of the bottom of the complete apparatus with the door for the recording mechanism swung 40 open; and

Figs. 10 to 26 inclusive detail views to be referred to hereinafter.

Fig. 27 is a diagrammatic view of a part of a record web, showing one form of record 45 made by the machine.

Referring to the drawings, and in particular to Fig. 1, it will be seen that there are eight sets of counting wheels toward the front of the machine, arranged in four horizontal rows, each of which rows embraces 50 two sets of counting wheels, the set at the right in each row being a total indicating device.

Of the two sets of counting wheels in the first or top row, that set at the left, comprising three counting wheels 1^a, 1^b, 1^c, indicates the trip distance, that is to say, the distance traveled during a trip, while the set of counting wheels at the right, comprising three counting wheels 2^a, 2^b, 2^c, indicates the 60 total miles traveled by the vehicle while earning fares.

Of the two sets of counting wheels in the second row, that set at the left, comprising three counting wheels 3^a, 3^b, 3^c, indicates the 65 trip time, that is to say, the time spent during a trip, while the set of counting wheels at the right, comprising three counting wheels 4^a, 4^b, 4^c, indicates the total time spent by the vehicle while earning fares. 70

Of the two sets of counting wheels in the third row from the top, that set at the left, comprising four counting wheels, 5^a, 5^b, 5^c, 5^d, indicates the amount of the fare due for the trip, while the set of counting wheels at 75 the right, comprising four counting wheels 6^a, 6^b, 6^c, 6^d, indicates the total amount of fares earned by the vehicle.

Of the two sets of counting wheels in the fourth or bottom row, that at the left, comprising three counting wheels 7^a, 7^b, 7^c, indicates the charge for extras, for example, the extra charge for baggage, while the set of counting wheels at the right comprising three counting wheels 8^a, 8^b, 8^c, indicates 85 the total extra charges earned by the vehicle.

For brevity, the two indicators in the top row will be referred to hereinafter as the trip distance and total trip distance indicators, respectively, the two in the second row as the trip time and the total trip time indicators, the two indicators in the third row as the fare indicator and the total fare indicator, respectively, while the two indicators in the fourth or bottom row will be referred to as the indicator for extras and the total indicator of extras, respectively. 90

Of these indicators, the total indicators, that is to say, those at the right hand of the 100 the respective rows, need not be reset, while the others at the left are reset at the end of each completed trip, or at the beginning of a new trip.

The trip distance and total trip distance 105 indicators are actuated from the wheel of

the vehicle, but only when the vehicle is earning a fare, said indicators being uncoupled from the driving mechanism when the vehicle is not engaged by a passenger, so that even though moving about idly the trip distance and total trip distance indicators will not be actuated.

The trip time and total trip time indicators are actuated by a clock mechanism, 10 which is running continuously, the said indicators, however, being coupled to the clock mechanism only when the cab is engaged, and being disconnected from said clock mechanism when the cab is not engaged.

The fare indicator and total fare indicator may be actuated by three different means as follows:

First, by a setting means, which comprises a distance charge setting device and a time charge setting device, these devices being operated manually by the driver at the beginning of a trip to set up an initial or basic charge on the fare indicator and 25 total fare indicator, the basic charge varying according to whether the vehicle is hired on the basis of a charge for distance traveled or for time spent and also according to the number of passengers, as more 30 fully explained hereinafter.

Second, if the vehicle is hired on the basis of a charge for distance traveled, then when the vehicle has traveled a basic distance for which the basic charge set up initially upon the fare indicator is the proper fare, then any further travel of the cab during that engagement necessitates a further charge. Therefore, as soon as the vehicle has exceeded the basic distance, the trip distance indicator automatically couples the fare indicator to mechanism operated by the vehicle wheel, after which the said fare indicator and also the total fare indicator are operated by the vehicle wheel to indicate the amount of fare due from the passenger for the distance traveled.

Third, if the basis of the charge to be made is the time spent on the trip, the charge initially set up on the fare indicator is the 50 basic charge for an engagement on a time basis. As soon as the vehicle has been in service to the passenger for a basic time corresponding to the basic charge initially set up on the indicator by the driver, then 55 for all further time spent in the employ of the passenger a further charge must be made.

Hence, as soon as the basic time is exceeded, the trip time indicator automatically couples the clock-mechanism to the fare indicator and to the total fare indicator, so that from that time on the said indicators are operated by the clock mechanism.

65 Furthermore, the setting mechanism by

which the driver sets up the basic charge on the fare indicator, is so constructed that it may not only set up a basic charge varying according to whether the charge is to be by time spent or distance traveled, but also as 70 to the number of passengers to be carried. For example, the basic charge for one or two passengers is less than that for three or four passengers, whether the said basic charge is for time or distance.

In other words, the setting device may be operated to set up on the fare indicator any one of four basic charges, namely, first for one or two passengers, for time; second, for one or two passengers, for distance; third, 80 for three or four passengers, for time; and fourth, for three or four passengers, for distance.

Furthermore, the rate at which the clock mechanism or the vehicle wheel drives the fare indicator, after being coupled to it, is different when the basic charge is set up for one or two passengers from what it is when the basic charge is for three or four passengers.

Hence, means is provided for varying the rate at which the fare indicator is driven by the clock work and also means is provided for varying the rate at which the fare indicator is driven from the vehicle wheel, 90 and these rate-varying means are adjusted by the setting mechanism, so that when the driver sets up the initial or basic charge on the fare indicator, according to time or distance, and according to the number of passengers, he also, at the same time, determines the rate at which the fare indicator is thereafter driven by its appropriate driving mechanism.

As it sometimes occurs that a vehicle 105 hired on the basis of a charge for distance traveled may be stopped for the benefit of the passenger during which time, of course, the trip-distance indicator and the fare-indicator could not be operated from the vehicle-wheel, a mechanism is provided which automatically couples the clock to the fare indicator during the time the vehicle is stopped, so that in this interval the fare-indicator is being actuated to charge up 110 fares according to a time basis. As soon as the vehicle starts again, the clock-mechanism is uncoupled and the fare-indicator is again operated as before from the vehicle-wheel.

Means is also provided for disconnecting the fare-indicator and total fare indicator from the operating mechanism in case of a break-down, so that no charge will be made to the passenger during such break-down.

The indicator for extras and the total indicator for extras are operated by manual means actuated by the driver.

As the various pairs of indicators are similar in construction, a specific descrip-

70

75

90

100

110

115

120

125

130

tion will be given first of the trip distance and total trip distance indicators.

The trip distance indicator comprises three counting wheels 1^a , 1^b , 1^c , revolvably mounted on a shaft 9, normally held stationary by a resetting mechanism, as more fully explained hereinafter. Each wheel comprises a hub, a cylindrical or drum-like periphery, and a web connecting the hub and periphery, this web being at one side of the wheel. (Fig. 22). To each of the wheels 1^b and 1^c is fixed a ratchet wheel, as indicated at 10, while to wheel 1^a is fixed a ratchet wheel 101 which may be smaller than ratchet wheels 10, Figs. 16 and 22. Between the respective pairs of counting wheels, for example the counting wheels, 1^a and 1^b and 1^c , and outside the highest counting wheel, there are arranged disks 11, each of which is fixed to the shaft 9 by means of a key 11^b fitting in the key way 9^a, and has a notch 11^a in its periphery, as shown in Figs. 11 and 22. To the left hand sides of the wheels 1^a , 1^b and 1^c are secured arms 12, each arm carrying a spring pawl, 13, provided with a nose or projection 14 which may ride on the periphery of its corresponding disk 11 and drop into the notch in said disk when opposite the same, said nose being arranged to engage the ratchet-wheel 10 of the next higher counting wheel, whenever said nose 14 drops into the notch in the corresponding disk 11.

The ratchet-wheel 101 of the wheel 1^a is actuated as follows:

Upon the shaft 9, between the trip distance indicator and the total trip distance indicator is located an oscillatory device having two arms, 15 and 16, connected by a sleeve 17, surrounded by a spring 18, one end of which is fixed to the frame of the apparatus. The arm 15 carries a pawl 19, Fig. 16, arranged to engage the ratchet-wheel 10^a of the wheel 1^a . Also said arm 15 is provided with a pin 20, arranged to be struck by the teeth of a star-wheel 21, mounted on a rotatable shaft 22 driven by suitable means, as hereinafter explained. When the star-wheel rotates, it encounters the pin 20 and pushes the arm 15 backward against the action of the spring, 18, that is to say, toward the left in Fig. 16. As soon as the tooth of the star-wheel clears the pin 20, the spring 18 throws the arm 15 forward and the pawl 19 rotates the ratchet-wheel 10^a of the counting wheel 1^a to an extent sufficient to move the counting wheel 1^a one indication.

When the counting wheel 1^a has been moved through nine indications, the spring pawl 13 of the said counting wheel 1^a enters the notch in its disk 11, and engages the ratchet-wheel 10 of the counting-wheel 1^b , so that when the counting wheel 1^a is moved from its 9th to its 10th or zero indication,

that is to say, when completing its revolution, the counting wheel 1^b is moved one indication, at the end of which time, the spring pawl of the wheel 1^a rides out of the notch in the disk 11, and thus is freed from the ratchet-wheel 10 of the wheel 1^b . Thus for every revolution made by the counting wheel 1^a the counting wheel 1^b is moved one indication, or one revolution for every ten revolutions of the wheel 1^a . In a similar manner the counting wheel 1^c is moved one indication for each revolution of the counting wheel 1^b . 70 75

The counting wheels 2^a , 2^b , 2^c , of the total trip distance indicator, are narrower than the wheels 1^a , 1^b , 1^c , and each is provided with a series of ratchet notches in its periphery. The ratchet notches in the periphery of the first counting wheel 2^a are arranged to be engaged by a pawl 23 Fig. 16, 80 85 carried by the arm 16, so that as said arm is oscillated, with the arm 15 as hereinbefore described, the counting wheel 2^a will be rotated step by step.

Between the counting wheels 2^a and 2^b 90 and 2^b and 2^c are arranged notched disks 24, secured to a stationary shaft 25. (See Fig. 21). The counting wheels 2^a and 2^b are each provided with spring pawls 26, each of which has a pawl tooth arranged to ride on 95 the side of the adjacent disk and to enter the notch in said disk, whereupon said pawl-tooth may engage a notch in the side of the next counting wheel, these notches being indicated at 27, Fig. 20. This construction 100 of the mechanism for carrying the tens and hundreds from the units wheel to the tens wheel and from the tens wheel to the hundreds wheel respectively, is similar to that employed in connection with the trip distance indicator, except that the spring pawls 26 act in the direction of the axis of the counting wheels instead of radially toward the center. 105

The shafts 9 and 25 have their axes in 110 line with each other, the shaft 25 being fixed in bearings 28 and 29, while the shaft 9 has one end journaled in the adjacent end of the fixed shaft 25, while its other end is supported by the bearing 30.

Upon the end of said shaft 9 is fixed a gear-wheel 31, which is one of the train of gears constituting part of the resetting apparatus which will be more fully described hereinafter. 115

When the said gear-wheel 31 is turned one complete revolution in the direction of the arrow, Fig. 11, it turns the shaft 9 and all the disks 11 one complete revolution. As the disks turn, the pawl teeth of the spring-pawls 13, enter the notches in the disks, and thereby the respective counting wheels are locked together in proper relation to each other by the spring pawls and are carried around until in their zero position. 120 125 130

tions, at which time the revolution of the disks 11 is completed.

In order to hold the counting wheels 1^a, 1^b, 1^c and the counting wheels 2^a, 2^b, 2^c in any position to which they may be set, suitable click-springs are provided, which are stationary and arranged to engage notches in the peripheries of the counting wheels. This form of device is old and well-known in the art. Therefore, in order not to complicate the drawings, the said click-springs have been omitted from the drawings, these click-springs, however, being similar to the click-spring for the total indicator for extras as shown at 32, Fig. 3.

The trip-time and total trip-time indicators are similar in construction to the trip-distance and total trip-distance indicators hereinbefore described, and are operated by a star-wheel 33 mounted on a shaft 34, the gear-wheel for resetting the trip-distance indicator being shown at 35, Fig. 1, to whose hub is fixed another gear-wheel 36 forming part of the resetting train.

The fare-indicator and total fare indicator are also similar to the trip-distance and total trip-distance indicators hereinbefore described, with the exception that each has four counting-wheels, 5^a, 5^b, 5^c, 5^d and 6^a, 6^b, 6^c, 6^d instead of three. Furthermore, instead of the two operating arms which carry the pawls being in different planes transverse to the axis of the counting wheels, as are the arms 15, 16, of the hereinbefore described indicators, the corresponding operating arms 15^b, 16^b, for the fare indicator and total fare indicator are placed substantially in the same transverse plane, as will be clear from Fig. 1, in order to economize space.

These arms are operated by a star-wheel 37 mounted on a shaft 38. The gear-wheel for resetting the trip-fare indicator is shown at 39.

The indicator of extras and the total indicator of extras is similar to the trip-distance and total trip-distance indicators, but its operating star-wheel 40 is normally out of the path of the pin 20^c on the arm 15^c, and is only pushed into said path when it is desired to operate the indicators, which, as hereinbefore explained, is done manually by the driver. To permit this to be done, the star-wheel 40 is mounted upon a longitudinally-movable tubular shaft 41 which is guided by a bearing 42 and by a rod 43, the latter extending into the interior of the tubular shaft. A spring 44 surrounding the rod 43 serves to press the shaft 41 normally outward so as to keep the star-wheel 40 out of engagement with the pin 20^c. The longitudinal movement of the shaft 41 is limited in one direction by a pin 45 and in the other direction by a collar 46.

The outer end of the shaft 41 extends be-

yond the casing of the apparatus and is arranged to be operated by a suitable key. When the driver desires to set up an indication of the charge made for extras, he pushes the shaft, 41, inward against the action of the spring 44 until the collar 46 contacts with the key or bearing 42, whereupon he rotates the shaft 41 in the proper direction. At this time the star-wheel 40 is in position to engage the pin 20^c and therefore the rotation of the star-wheel will cause the arms 15^c and 16^c to oscillate and thereby move the indicators step by step until the indicator of extras exhibits the desired charge for extras, whereupon the driver releases the shaft 41, which is forced outward by the spring 44, so as to release the star-wheel from the pin.

For the purpose of resetting the indicator of extras, the shaft 9^c Fig. 11 of the said indicator is provided with a gear-wheel 47. An additional gear-wheel 48 is also provided for a purpose hereinafter explained.

The operating shaft 22 for the trip distance indicator and its totalizing indicator is operated as follows:

Upon the shaft 22 is fixed a bevel-gear wheel 48^a, which meshes with a bevel-gear wheel 49 fixed to a vertical shaft 50, journaled in bearings 50^a, 50^b, and 50^c. The lower end of this shaft 50 is provided with a movable clutch-member 51 splined to the shaft and arranged to be shifted into engagement with a clutch-member 52, mounted upon a stud 53, Figs. 1 and 5, and united to a gear-wheel 54 which is connected, through an intermediate idler wheel, 55, carried by a stud 56, with a pinion 57, mounted on a stud 58 and connected to a ratchet wheel 59, arranged to be engaged by a pawl 60, carried by a pawl lever 61, normally pressed by a spring 62 toward a cam 63, mounted on a main driving shaft 64 arranged to rotate from the vehicle wheel by suitable mechanism.

When the vehicle is traveling and its wheels are thereby rotated, the said shaft 64 will be rotated and the cam 63 will oscillate the lever 61, whose pawl 60, will move the ratchet wheel 59 and with it the gear-wheel 54, whereby the clutch-member 52 is rotated. If now the clutch-member 51 is in engagement with the clutch-member 52, the shaft 50 will be operated and with it the shaft 22, through the bevel gears, 48^a and 49, thus causing the star-wheel 21 to actuate the trip-distance and total trip-distance indicators.

The trip time and total trip time indicators as hereinbefore explained are operated by the star-wheel 33 on the shaft 34. This shaft is rotated from a clock-mechanism, during the time the vehicle is under hire, as will now be explained.

The clock mechanism indicated generally by the reference numeral 65, Fig. 4, is of

any usual or desired construction and is located at the upper rear portion of the taximeter. Its spring is indicated at 66, its winding arbor at 67, and its main arbor at 68. The latter is provided at its front end with a bevel gear wheel 69, Fig. 10, fixed to the main arbor and meshing with a bevel gear wheel 70 on a vertical shaft 71, the purpose of which will be more fully explained hereinafter.

Upon the extreme front end of the main arbor 68 is loosely mounted a compound crown and bevel gear wheel 72, best shown in Fig. 10, this wheel having crown gear teeth on its front face and bevel gear teeth on its rear face.

Between the crown and bevel gear wheel 72 and the bevel gear wheel 69 there is a clutch mounted upon the arbor 68, one clutch-member 73 being secured to the back of the crown and bevel gear wheel 72 while the shiftable member 74 of the clutch is splined to the arbor 68 and is adapted to be shifted by a lever 75 actuated by means more fully explained hereinafter.

The clock-mechanism is intended to be in continuous operation. When the clutch members 73 and 74 are locked together, the clock mechanism will rotate the crown and bevel gear wheel 72. This is in mesh with a gear-wheel 76 fixed on the shaft 34, Fig. 1, whereby the latter is rotated to actuate the trip-time and total trip-time indicators. When the vehicle is not engaged the clutch members 73 and 74 are separated so that the trip-time and total trip-time indicators are not operated, although the clock mechanism continues to run.

The fare indicator and total fare indicator as hereinbefore explained are actuated by the star-wheel 37 located on the shaft 38. This shaft is provided with four gear-wheels 77, 78, 79 and 80, and with a bevel gear wheel 81. At 82 and 83 are indicated the bearings for the said shaft.

Below the shaft 38 is located a shaft 84 having one end of reduced diameter journaled in a hole in the shaft of the fare indicator, and its other end journaled in the bearing 50^b. Upon this shaft 84 are loosely mounted gear wheels 85, 86, 87 and 88, which mesh with the gear wheels 77, 78, 79 and 80, respectively. The gear wheels 85 and 86 are provided on their opposing faces with clutch members, arranged to be engaged alternately by a clutch member 89 splined to the shaft 84, and capable of being shifted one way or the other or held in an intermediate inoperative position by a lever 90, as more fully explained hereinafter.

The gear-wheels 87 and 88 are similarly provided with clutch-members arranged to be engaged alternately by a clutch member 91, splined to the shaft 84 and capable of be-

ing shifted one way or the other or held in an inoperative intermediate position by a lever, 92, as more fully explained hereinafter.

To the end of the shaft 84 is fixed a bevel gear wheel 93, meshing with a bevel gear wheel 94 attached to a sleeve 95, said wheel 94 and sleeve 95 being loosely mounted upon the shaft 50, the sleeve however having its upper end formed as one member of a clutch, the other clutch member 96 being provided with pins 97 arranged to enter holes in a bevel gear 98, in mesh with a bevel gear wheel 99. The clutch member 96 normally is locked to the sleeve 95, being unlocked from it manually only in case of break-downs of the vehicle, as more fully explained hereinafter. When the clutch member 96 is locked to the sleeve, the rotation of the bevel gear 99, as more fully explained hereinafter, will cause the rotation of the bevel gear wheels 94 and 93 and of the shaft 84.

The shaft 38 will be driven from the shaft 84, when any one of the gear wheels 85, 86, 87 or 88 is locked to said shaft 84 by its respective clutch member 89 or 91. Since the ratios of transmission of the meshing pairs of gear-wheels, 85 and 77, 86 and 78, 87 and 79, 88 and 80 are different for the different pairs, the speed of the shaft 38 can have any one of four different ratios relative to the shaft 84, dependent upon the particular pair of gear-wheels serving to transmit the power from shaft 84 to shaft 38.

The bevel gear wheel 99 is loosely mounted on a stud 100 secured to a bearing member 101, and has holes engaged by pins 102, Fig. 25, carried by a clutch-member 103, arranged to engage a corresponding clutch-member 104, which is united with a pinion 105 in mesh with the crown-gear-wheel 72. The latter, as hereinbefore explained, is driven by the clock-mechanism, and when the clutch members 103 and 104 are locked together, the bevel gear wheels 99 and 98 are also driven by the clock-mechanism so that through the clutch 96 the sleeve 95 and bevel gear-wheels 94 and 93 the shaft 84 is rotated by the clock-mechanism, and from the shaft 84 the fare-indicator and total fare-indicator are operated as hereinbefore described.

The clutch members 103 and 104 are locked together by a clutch lever 106 in a manner hereinafter described.

The shaft 84 also may be rotated from the wheel of the vehicle by the following means:

The bevel gear wheel 98 is provided with a long sleeve 107 having a clutch-member 108, arranged to be engaged by a double clutch member 109 having clutch teeth on two faces, as shown in the drawings. The upper set of clutch teeth are arranged to engage with the teeth on a clutch member 110 provided with pins 111 which enter holes 112

in the hub of the bevel gear wheel 49, which is fixed to the shaft 50.

The teeth connecting the clutch members 109 and 110 are long enough so that the member 109 can be moved by a clutch lever 112, into engagement with the clutch member 108 without being disengaged from the clutch member 110.

When it is desired to release the clutch members 109 and 110, the clutch member 110 is moved upward by the clutch lever 113, the forked end of which is seen in plan in Fig. 1, and which is also shown in Fig. 2 in engagement with pins 199. This, however, is done only in case of a break down of the vehicle.

When the clutch members 109 and 108 are engaged with each other, the clutch members 103 and 104 which couple the clock mechanism to the fare indicator are disengaged. Under this condition the fare indicator is driven from the vehicle wheel through the shaft 50, bevel gear 49, pins 111, clutch members 110, 109, 107, bevel gear 98, pins 97, clutch member 96, sleeve 95, bevel gears 94 and 93, and shaft 84, which transmits its motion to the shaft 38 through the particular pair of gear-wheels at that time in action.

In addition to the means for driving the fare-indicator and fare-indicator shaft from the clock mechanism, as hereinbefore described, a supplemental mechanism is provided which is automatically held out of action when the vehicle is traveling, but which comes into use as soon as the vehicle stops. This supplemental mechanism which couples the star wheel shaft 38 to the clock-mechanism, is as follows:

Upon the shaft 38 is journaled a swinging bracket 114, Figs. 1 and 10, having a rearward extending arm 115 normally drawn upward by a spring 116.

In this bracket is journaled a shaft provided at each end with a bevel gear wheel, these wheels being indicated at 117 and 118, Figs. 1 and 10. The bevel wheel 117 is arranged to engage the bevel gear portion at the back of the compound crown and bevel gear wheel 72. The lower bevel gear wheel 118 meshes with the bevel gear wheel 81 on the shaft 38.

At 119, Fig. 10, is arranged a trip lever, pivoted at 120 and having an inclined nose 121 at the lower end, against which the pawl lever 61, Figs. 5 and 10 may strike, whereby the lower end of the trip-lever is pushed backward on the downward movement of the pawl lever 61.

The upper end of the trip lever is arranged to strike and swing downward the arm 115. Said upper end is connected to a delay action device such for example as the dash-pot mechanism indicated in Fig. 10. This mechanism comprises a dash-pot

cylinder 122 within which is a piston 123, provided with a rod coupled to the end of the lever 119.

The dash-pot cylinder 122 has an air-inlet at its bottom, over which rests loosely a valve 124.

When the pawl lever 61 moves downward it moves the lower end of the trip-lever backward, and thus forces the upper end of the trip lever forward, drawing the piston 123 forward in the cylinder 122, the valve 124 lifting to allow the outside air to enter behind the piston. At the same time the upper end of the trip lever 119 swings the arm 115 downward against the action of its spring 116, and thereby disengages the bevel gear wheel 117 from the bevel gear portion of the wheel 72. The spring tends to move the arm 115 upward, and thereby to press the upper end of the lever 119 backward, but the piston 123 prevents this being accomplished rapidly, since on the rearward movement of the piston the valve 124 is closed by the compression of the air behind the piston, which air escapes but slowly around the valve. Hence if the oscillating pawl lever 61 is in operation, due to the rotation of the vehicle wheel, it will at each downward movement push the trip lever 119 so as to swing the arm 115 downward, and as the said arm does not have time to move upward far enough to allow the gear-wheel 117 to mesh with the gear wheel 72, before said arm is again moved downward, the said bevel gear 117 is maintained out of contact with the gear-wheel 72, so long as the vehicle wheel is rotating, even slowly. However, if the vehicle stops, the lever 119 is no longer oscillated by the pawl lever 61, and hence the spring 116 can gradually draw the arm 115 upward, depressing the piston 123 of the dash-pot mechanism.

Thereupon the bevel gear 117 engages the gear-wheel 72 and the clock mechanism drives the bevel gears 117, 118 and 81, thus rotating the shaft 38 and actuating the fare indicator and total fare-indicator.

The setting mechanism comprises two transversely arranged setting shafts 125 and 126, whose rear ends extend outside the casting and are provided with notched disks 127 and 128, Figs. 12 and 15, each fixed to its respective shaft and having a hub provided with notches as indicated at 129, arranged to receive the end of a key by means of which the respective shaft may be turned by hand. Each of the disks 127 and 128 has an index 130, 131, arranged to coact with certain indications, as indicated in Fig. 15.

A rod 132 is mounted at the back of the apparatus, with its axis in a vertical plane between the two disks 127 and 128. This rod has two cams 133 and 134 at its lower end, as will be clear from Figs. 14 and 15.

At the upper end of the rod 132 are trans-

verse pins 135 and 136 arranged opposite a swinging indicator 137, hinged on a pintle pin 138, Figs. 7 and 15 supported in ears 139 at the upper end of the casing. A 5 spring 140 normally tends to hold the swinging indicator upright.

When the disk 127 is rotated the edge 141 at the bottom of the notch engages the inclined cam surface of its cam 133 and thereby rotates the rod 132 in the direction of the arrow, Fig. 14, thereby forcing the swinging indicator 137 downward to a horizontal position, against the action of its spring 140. At the same time the cam 134 15 is swung outward so that its flat bottom is brought into the plane of the disk 128, thus preventing this disk from being rotated while the disk 127 is set.

When the disk 127 is moved back to its 20 normal or zero position, the spring 140 raises the swinging indicator 137 and also rotates the rod 132 to its normal position. The swinging indicator is provided with a legend indicating that the vehicle is not engaged, as for example, the legend "To let" 25 shown in Fig. 6.

When the disk 128 is rotated to the left, Fig. 15, the edge 142 of the disk at the lower end of its notch engages the cam surface 30 of the cam 134 and rotates the rod 132 in a direction opposite that indicated by the arrow, whereby the swinging indicator is forced down to a horizontal position against the action of its spring 140, by the pin 136, 35 and the other disk 127 is locked by the cam 133.

The shaft 125 is intended to be rotated when the vehicle is hired for one or two passengers and the shaft 126 is to be rotated 40 when the vehicle is hired for three or four passengers.

The extent to which the shafts 125 and 126 are to be rotated in the respective directions depends upon whether the vehicle 45 is hired on a basis of a charge for time or for distance. If the former the respective disk is rotated to an extent sufficient to bring its index 130 or 131 opposite the indication marked "Time". See Fig. 15. If 50 on the other hand the charge is to be based on distance traveled, the respective disk is moved until its corresponding index comes opposite the indication marked "Distance".

Upon the forward end of each of the 55 shafts 125 and 126 are mounted three cams, and a bevel gear wheel. The cams are indicated at 142^a, 143^a, 144^a, 142^b, 143^b, 144^b, respectively, while the bevel gears are indicated at 145^a and 145^b respectively. See 60 Figs. 10, 12 and 23.

Upon a transverse shaft 146, Figs. 10 and 12, are loosely mounted two cam levers, 147 and 148, secured to each other and to a clutch lever 149, Figs. 12 and 13, the said 65 clutch lever 149 being arranged to engage

and operate the clutch member 51, Figs. 7 and 12, which serves to couple the shaft 50 to the vehicle wheel, and having a projecting forked end 149^a which engages a pin 197^a on a rod 197 (Fig. 2) and holds up the 70 same to keep the clutch members 73 and 74 uncoupled as more fully explained hereinafter.

The cam levers 147 and 148 ride against the cams 144^a and 144^b respectively. These 75 cams have their peripheries so arranged that when the index 130 is moved to either of the indications marked "Time" and "Distance" the cam 144^a will move the lever 147 to the left in Fig. 12 and shift the clutch 80 lever 149 so as to lock the clutch members 51 and 52, whereby the vehicle wheel may drive the shaft 50.

Furthermore, when the index 131 moves to the indications marked "Time" or "Distance" 85 the cam 144^b will move the lever 148 so as to accomplish the same result of locking the clutch.

Upon the shaft 146 are also mounted two arms 151 and 92, the former being pressed 90 against the cam 143^b by a spring 152, while the latter arm 92 serves as the clutch lever for throwing the clutch member 91 to the right or left, so as to lock either the gear wheel 88 or the gear wheel 87 to the shaft 84. 95

At 153 is a stud or shaft upon which two arms 154 and 90 are pivoted, these arms being secured to each other.

The arm 154 is held against the cam surface 143^a by a spring 155, while the arm 90 100 serves as a clutch lever for throwing the clutch member 89 to the right or left so as to lock either the gear wheel 86 or the gear wheel 85 to shaft 84.

The bevel gear wheels 145^a and 145^b Fig. 10, serve to set up the basic fare on the fare indicator. For the purpose of accomplishing this result the following mechanism is employed.

Upon the shaft 84 is loosely mounted a 110 pinion 156 Figs. 1 and 23 secured to the gear wheel 88, said pinion being engaged by a gear wheel 157 loosely mounted on a shaft 158, Figs. 1, 11 and 23. At each side of the gear wheel 157 is a ratchet wheel, said 115 ratchet wheels being shown at 159 and 160, respectively. The ratchet wheels are loose upon the shaft 158 and have their teeth projecting in the same direction. Upon each side of the gear wheel 157 is pivoted a 120 spring pressed pawl 161, 162, each of which engages its respective ratchet-wheel.

To each ratchet wheel is fixed a gear wheel, and a bevel pinion, the gear wheels being indicated at 163 and 164 and the bevel 125 pinions at 165 and 166, said gear wheels and bevel pinions also being loosely mounted upon the shaft 158. The gear wheels 163 and 164 form part of the resetting mechanism, hereinafter referred to. The bevel 130

pinions 165 and 166 mesh with their respective bevel gear wheels 145^a and 145^b.

The ratio of transmission between the bevel gear wheels 145^b and 165 is different from that of the bevel gears 145^a and 166.

The operation of the setting mechanism thus far described is as follows:

The setting apparatus provides for setting up four different basic charges on the fare indicator, namely,

First, for one or two passengers, by distance,

Second, for one or two passengers, by time,

Third, for three or four passengers, by distance,

Fourth, for three or four passengers, by time.

Under the first condition the shaft 125 Fig. 15 is turned to the right by the driver until the index 130 points to the indication marked "Distance." This causes a rotation of the bevel wheel 145^a and of the cams mounted on the shaft 125.

The rotation of the bevel wheel 145^a causes a rotation of the bevel pinion 166 in mesh with it and thereby rotates the ratchet wheel 164 in such a direction as to engage the pawl 162 and rotate the gear wheels 157, 156, 88 and 80, thus rotating the star-wheel shaft 38, whose star-wheel 37 actuates the fare indicator to set up the proper basic fare.

The rotation of the cam 144^a causes the cam lever 147 to swing the clutch lever 149 and lock the clutch members 51 and 52, (Fig. 12), said cam lever simultaneously lowering the rod 197, and locking the clutch members 73 and 74 (Fig. 10) whereby the clock mechanism is coupled to the crown and bevel gear wheel 72, as more fully explained hereinafter. Furthermore, the rotation of the cam 143^a moves the arm 154 so as to swing the clutch lever 90 to the left, Figs. 1 and 2, thereby locking the clutch member 89 to the gear wheel 85.

The arrangement of the cams 144^a and 143^a is such that the locking of the clutch members 51 and 52 and of the clutch member 89 to the gear wheel 85 takes place toward the end of the movement.

It is to be noted, however, that although the shaft 50 is coupled by the clutch members 51 and 52 so as to drive the trip distance indicator as soon as the vehicle starts, still, the fare indicator will not be operated, because the clutch members 108 and 109 are still open. These clutch members are not locked together until the vehicle has traveled a basic distance equivalent to the basic charge set up on the fare indicator. At the end of this basic distance the said clutch members 108 and 109 are locked together, by the action of the trip distance indicator as

hereinafter explained, whereupon the shaft 65 50 drives the shaft 84, and the latter drives the shaft 38 through the gear wheels 85 and 77, thus continuing to actuate the fare recorder at a rate proportional to the revolutions of the vehicle wheel, the ratio being determined by the ratio of transmission of the gear wheels 85 and 77.

Of course it will be understood that each movement of the fare indicator is accomplished by a corresponding simultaneous movement of the total fare indicator, so that all charges made on the former are also made on the latter.

Under the second condition, the shaft 125 is turned to the right by the driver until the index 130 points to the indication "Time." Obviously, this requires a greater angular movement of the shaft 125 than when the index is stopped at the indication "Distance." Thus the bevel wheel 145^a is rotated to a greater extent than under the condition where the basic charge is made by distance.

Consequently, the said bevel gear wheel 145^a rotates the gear wheels 157, 156, 88 and 80 in the same manner as under the first condition, but to a greater extent so that the shaft 38 and its star-wheel 37 are also rotated to a greater extent and a greater basic charge is set up on the fare indicator.

The cam 144^a actuates the arm 147 and clutch lever 149 to lock the clutch members 51 and 52 as hereinbefore described under the first condition, and to couple the clock-mechanism to the crown and bevel gear wheel 72. In closing clutch 51—52, the clutch lever 149 with its projecting fork 149^a, Figs. 2 and 13, moves away from pin 197^a and allows rod 197 to be forced downward by means of the spiral spring 197^b acting against the pin 199. In its downward movement, shaft or rod 197 carries with it lever 201 by means of the pins 200 which pass through 197 on either side of lever 201. Lever 201 is firmly fixed to one end of a rotatable shaft 202 to which clutch lever 75 is also firmly fixed, Figs. 2 and 10. From the above description it will readily be seen that a movement of rod 197 in either direction will either open or close clutch 73—74.

Furthermore, the cam 143^a at first actuates the arm 154 and clutch lever 90 as hereinbefore described, to move the clutch member 89 to the left, after which the further movement of said cam moves the clutch lever 90 to the extreme right so that the clutch member 89 is locked to the gear wheel 86, whereby any subsequent rotation of the shaft 84 will be transmitted to the shaft 38 through the gear wheels 86 and 78.

The fare indicator after receiving the basic charge for time, is not again actuated until an interval of time, equivalent to the

basic charge, has expired. Thereupon the clutch members 103 and 104 are locked together by the automatic action of the time indicator, as hereinafter explained, so that 5 thereafter the clock mechanism drives the shaft 84 through the gear wheel 72, pinion 105, bevel gears 99 and 98, sleeve 95 and bevel gears 94 and 93. The gear wheels 86 and 78 transmit this rotation of the shaft 10 84 at the proper ratio, to the star wheel shaft 38, so that the subsequent charges will be made at regular intervals upon the fare indicator, and of course, also upon the total fare indicator.

- 15 It is to be understood, of course, that when an engagement of the vehicle either for distance or time has terminated, the shaft 125 is rotated back to its zero position, in which 20 position the clutch member 89 is not locked 25 to either gear wheel 85 or 86, the clutch members 51 and 52 and the clutch members 73 and 74 are unlocked.

Under the third condition, namely, when the charge is to be made for three or four 30 passengers for distance, the shaft 126 is turned to the left by the driver, until the index 131 points to the indication "Distance." This causes a rotation of the bevel gear wheel 145^b and of the cams connected 35 with it.

The rotation of the bevel wheel causes a rotation of the bevel pinion 165 and of the ratchet wheel 159 in such a direction that it 40 engages the pawl 161 and turns the gear wheels 157 and 156 so that the gear wheels 88 and 80 are rotated in the same manner as hereinbefore described under the first condition. However, the ratio of transmission between the bevel gear wheel 145^b and its 45 bevel pinion 165 is such that the basic fare set up on the fare indicator is greater than under the first condition.

The rotation of the cam 144^b swings the arm 148 and with it the clutch lever 149 so 50 as to lock the clutch members 51 and 52, and to couple the clock-mechanism to the crown and bevel gear wheel 72. Also the rotation of the cam 143^b moves the arm 151 and with it the clutch lever 92, which shifts 55 the clutch member 91 to the left, Figs. 1 and 12 and thus locks the said clutch member 91 to the gear wheel 87, whereby any subsequent rotation of the shaft 84 will be transmitted through the gear wheels 87 and 79 to the shaft 38.

It is to be understood that under this condition, as well as under the first condition, the shaft 84 is not coupled to the shaft 50, through the clutch members 108 and 109, 60 until the basic distance for which the basic charge is made has been traveled by the vehicle. As hereinbefore explained, the said clutch members 108 and 109 are locked automatically by the trip distance indicator,

by means which will be more fully described 65 hereinafter, this locking being done only after the vehicle has traveled a basic distance corresponding to the basic fare set up on the fare indicator.

Under the fourth condition, the shaft 126 70 is turned to the left by the driver until the index 131 points to the indication marked "Time," this, of course, giving a greater angular movement of the shaft 126 than when the index 131 was moved merely to 75 the indication "Distance." This greater angular movement of the shaft 126 causes also a greater movement of the bevel wheel 145^b and thereby, through the connected gearing, of the shaft 38, so that a greater 80 basic charge is set up on the fare indicator than under the third condition.

During the first part of the movement of the shaft 126, the clutch members 51 and 52 are locked together, as hereinbefore described, under the third condition.

Also, during the first part of the movement of the shaft 126, the clutch member 91 is moved to the left and locked to the gear wheel 87, but during the latter part of the 90 rotation of the shaft 126 said clutch member 91 is shifted to the extreme right (Fig. 12) and is locked to the gear wheel 88. After the lapse of the time interval for which the basic charge is made, the clutch members 95 100 103 and 104 are locked together automatically by the trip time indicator, as will be explained hereinafter, so that from that time on, the clock mechanism will actuate the fare indicator, through the gear wheel 72, pinion 105, bevel gears 99 and 98, clutch member 96, sleeve 95, bevel gears 95 and 93, shaft 84, gear wheels 88 and 80, shaft 38 and star wheel 37. The gear wheels 88 and 80 have a ratio of transmission so selected 105 as to give the proper rate of charge for the fourth condition.

When the shaft 126 is moved backward to set the index 131 to zero, the clutch member 91 is brought to its intermediate position, 110 so that it is not in engagement with either gear wheel 87 or 88. Also the clutch members 51 and 52 and the clutch members 73 and 74 are unlocked.

For the purpose of enabling the passenger 115 to see that the apparatus is set as should be under the condition for which the vehicle is hired, two indicators operated by the setting mechanism are provided.

These indicators may be of any suitable 120 form, but in the construction illustrated, the indicators are made as segments of hollow cylinders, as shown at 167 and 168, Fig. 17 each pivoted on an axis, 169 and 170, to each of which is fixed a contact device, in the 125 present example shown as a triangular block, 171 and 172.

The upper indicator, which indicates the

number of passengers for which fare is being charged is so balanced that normally the central radius of the sector remains horizontal, as shown in Fig. 17. This indicator 5 carries two indications, namely, the indications 1 or 2 Fig. 6 arranged in a line near the upper edge of the indicator, and the words "Three or four" arranged in a line near the bottom edge of the indicator, the 10 intermediate space being blank. The front of the casing of the apparatus has a window opposite which the indicator is located. When the indicator of passengers is in its 15 zero position, the blank space of the said indicator is opposite the window.

When the indicator is swung down the top line containing the indications 1 or 2 comes opposite the window. When the indicator is 20 swung up, the bottom line containing the indications 3 or 4 comes opposite the window.

The lower indicator, which indicates whether the charge is by distance or time, is also arranged opposite a window in the front of the casing. Near its lower edge this 25 indicator bears the word "Time," and at its central portion the word "Distance," above which, along the upper edge, is a blank space.

When in its normal or zero position the 30 lower indicator swings down, as shown in Fig. 17, so that the blank space comes opposite the window. When the indicator is swung to a position when the radius at the middle of the segment is horizontal, the 35 word "Distance" appears at the window, and when the indicator is swung farther upward the word "Time" appears at the window.

In order to swing the indicators, the following mechanism is employed. See Figs. 40 12 and 17.

A shaft 173 is provided at one end with 45 an arm 174 pinned thereto and arranged to bear on the face cam 142^b, so that as said cam is rotated the arm 174 will be rocked by the cam, thereby rocking the shaft 173. At the other end an arm 175 is secured to the shaft 173, so that when the shaft is rocked the said arm 175 will be swung. This arm carries two pins, 176 and 177, the upper one, 50 176, being arranged to strike near the lower edge of the contact block 171, and push it forward, thus swinging the indicator 167 on its axis so as to bring the lower indication 3 or 4 opposite the window in the front of 55 the casing.

The lower pin, 177, is arranged to strike near the lower edge of the contact device 172 of the lower indicator 168 and thus swing said indicator upward.

60 The extent to which the said indicator is moved upward depends upon the extent to which the arm 175 is swung by the shaft 173, which in turn is determined by the cam 142^b. When the shaft 126, on which said

cam 142^b is fixed, is rotated to set the apparatus for a distance charge, the arm 174, shaft 173 and arm 175 are rocked just enough to swing the lower indicator to a position where the central radius of the segment is horizontal and the indication "Distance" appears at the window. When the shaft 126 is rotated to set the apparatus for a time charge, the arm 174, shaft 173 and arm 175 are rocked further, whereby the indicator is swung upward to the maximum amount and the indication "Time" appears at the window.

In order that this difference in the extent of movement of the lever 175 may not cause a difference in the extent to which the upper 80 indicator 167 is swung upward, the surface of the lower rear face of the contact block 171 is slightly rounded or beveled, as shown in Fig. 17, at the point struck by the pin 176.

Upon the shaft 173 is loosely mounted a 85 sleeve 178, to which is fixed an arm 179, arranged to bear against the face cam 142^a which is fixed on the shaft 125. When the cam is rotated it rocks the arm 179 and with it the sleeve 178. To the opposite end of the 90 sleeve is fixed an arm 180, also provided with two pins, 181 and 182, Fig. 17, the upper one, 181, being arranged to strike the upper edge of the contact block 171, and the lower pin, 182, being arranged to strike the lower edge 95 of the contact block 172.

When the arm 180 is rocked by the rocking of the sleeve 178 from the cam 142^a it will swing the indicator 167 downward and bring the indication 1 or 2 opposite the window.

At the same time, the lower indicator 168 is swung upward, by the pin 182, to indicate either "Distance" or "Time," according to the extent to which the arm 180 is rocked, 105 this depending upon the cam 142^a which is so arranged that when the shaft 125 is rotated to set the apparatus for a charge according to distance the lower indicator 168 will be moved to a horizontal position, and when the shaft 125 is rotated to set the apparatus for a charge according to time, the lower indicator 168 will be swung upward to its maximum extent.

In order that this two-stage movement of 115 the arm 180 may result in only a one-stage movement of the upper indicator 167, the contact surface at the upper rear edge of the contact block which is struck by the pin 181 is rounded or beveled off.

The upper indicator 167 is provided with a rearwardly extending arm 183 provided with a slot into which enters the end of a crank arm 184 secured on or forming part of a shaft 185, the purpose of which will be 125 explained hereinafter in connection with the description of the recording apparatus.

The means whereby the trip distance indi-

cator shifts the clutch member 109 so as to lock it to the clutch member 108 will now be described.

Referring to Figs. 1 and 18, 186 is a shaft 5 to which is fixed a clutch lever 112 which is forked to engage the peripheral groove of the clutch member 109 in the usual way. The end of the said lever is provided with a beveled face as shown at 188 for coöperation 10 with a corresponding inclined face of a light spring 189 bent as shown in Fig. 18. When the clutch lever 112 is forced downward to lock the clutch member 109 to the clutch member 108, its inclined surface 188 forces the 15 spring 189 forward, until the end of the said clutch lever clears the inclined face of the spring, whereupon the spring flies back and holds the clutch member 109 in engagement with the member 108. This spring 189 is 20 pushed forward to release the said clutch-lever 112, by an extension 181^a—182^a, one of the pins 199, when the rod 197 is moved to its normal position. This arrangement is 25 shown toward the left of Fig. 2, and also in the fragmentary plan of Fig. 24.

For the purpose of rocking the shaft 186 to move the clutch lever 112, the said shaft is provided with an arm 190, having an inverted V-shaped tooth, 191, arranged to be 30 struck and forced downward by a pin 192 carried by the first counting wheel of the trip distance indicator.

The operation of the above described mechanism is as follows:

35 When a basic fare for distance has been set up on the fare indicator, as has been explained hereinbefore, the clutch members 51 and 52 are locked together by the action of the setting mechanism, and thereby the shaft 40 50 is operated from the vehicle wheel when the vehicle is moving. The rotation of the shaft 50 and the star wheel shaft 22 rotates the star wheel 21 and thereby actuates the trip distance indicator. As soon as the first 45 counting wheel has been rotated an amount such as to indicate the basic distance traveled for which the basic charge is made, the pin 192, Fig. 18, comes into contact with the tooth 191 of the arm 190, so that any 50 further rotation of the said first counting wheel of the trip distance indicator will force said arm 190 downward, thereby rocking the shaft 186 and the clutch lever 112, whereby the clutch member 109 is shifted 55 downward into engagement with the clutch member 108, and is locked in this position by the spring 189.

As hereinbefore explained, the clutch teeth at the upper part of the clutch member 109 are long enough to stay in engagement with the clutch teeth of the member 110, even when the clutch member 109 has moved downward into engagement with the member 108.

After the members 108 and 109 are locked 65 together, the rotation of the shaft 50 by the vehicle wheel, during the traveling of the vehicle will actuate the fare indicator and total fare indicator as hereinbefore explained.

70

For the purpose of connecting the clock mechanism to the fare indicator, through the clutch members 103 and 104, as hereinbefore explained, the trip time indicator is arranged to lock said clutch members, through 75 the following mechanism.

The first counting wheel of the trip time indicator is provided with a pin 193 which actuates an arm 194, fixed on a shaft 195. This shaft carries a pin 196, Figs. 1 and 80 19, which engages one arm of the bell crank clutch lever 106.

Consequently, when the first counting wheel of the trip time indicator has rotated to an extent sufficient to indicate the basic 85 time for which the basic charge is made, its pin 193 rocks the arm 194, shaft 195 and pin 196, thus moving the bell crank clutch lever 106 and locking the clutch members 103 and 104, whereby the rotation of the gear wheel 90 72, driven by the clock mechanism, may be transmitted to the fare indicator as has been explained hereinbefore.

It is to be noted that as the trip time indicator and the trip distance indicator are 95 both in action when the vehicle is engaged, each will, after one revolution of its first counting wheel, shift its respective clutch member, 109 and 103, so that eventually the fare indicator is coupled to both the clock 100 mechanism and to the vehicle wheel. Consequently if, when a vehicle has been engaged on the basis of a time charge, the driver runs such vehicle at a rate of speed above a certain normal speed, the fare indicator will 105 be actuated by the vehicle wheels, or in other words, the charges will then be made really according to the distance traveled.

On the other hand, if when the vehicle is hired on the basis of a distance charge, the 110 driver travels slower than the normal rate of speed, the fare indicator will be operated by the clock mechanism, that is, the charges will be made according to the time spent.

This is possible because both the vehicle 115 wheel and the clock mechanism are coupled to the fare indicator at the same time, and the latter is actuated by whichever driving mechanism will cause the more rapid movement of the fare indicator.

For example, when the clutch members 109 and 108 and 103 and 104 respectively are locked together, and the vehicle is traveling so rapidly that the bevel gear wheel 98 will turn more rapidly than it could be driven by the uniformly moving clock mechanism, the result will be that the clutch member 103 will slip on the clutch member 120 125

104, like a pawl slipping on a ratchet wheel, this being possible owing to the use of the ratchet teeth on the said clutch members. On the other hand, if the vehicle is traveling so slowly that the bevel gear wheel 98 and the clutch member 108 connected to it are rotated by the clock mechanism more rapidly than the clutch member 109 is rotating under the action of the vehicle wheel, then the clutch member 108 will slip over the clutch member 109, owing to the ratchet teeth employed to connect the two.

In order that the driver may stop the operation of the fare indicator during a break-down, suitable means is provided for uncoupling the fare indicator from its actuating devices, this means being as follows:

A longitudinally movable rod 197 arranged vertically in the apparatus has its lower end projecting below the same when it may be provided with a suitable handle or knob as indicated at 198, Figs. 2 and 3.

This rod is provided with two sets of pins 199 and 200, the upper set 199 engaging the clutch lever 113 controlling clutch member 110 and the lower set 200 engaging a clutch lever 201, Figs. 2 and 3, which engages the clutch member 96.

Consequently, when the rod 197 is pushed upward to a sufficient extent by hand, the clutch member 110 is moved upward, and thereby unlocked from the upper clutch teeth of the member 109, while at the same time the clutch member 96 is moved upward and thereby unlocked from the clutch teeth of the sleeve 95. The said rod 197 is normally pressed downward by a spring 197^b and is locked in its raised position by a bayonet joint device indicated at 197^c. Furthermore, it is provided with a pin 197^a which is above the fork 149^a of the clutch lever 149, Fig. 2.

The clutch lever 201 is fixed on a shaft 202, Figs. 2 and 10, to which is secured the clutch lever 75. By this arrangement the clutch member 74 is unlocked from the clutch member 73, when the rod 197 is moved upward, whether by the upward movement of the clutch lever 149 or by hand, thus uncoupling the combined crown and bevel wheel 72 from the clock mechanism.

The amount of movement of the rod 197 necessary to move the clutch members 110 and 96 is greater than that necessary to unlock the clutch members 73 and 74, so that when the clutch lever 149 in returning to its normal position lifts the rod 197 it will unlock the clutch members 73 and 74 without affecting the members 110 and 96.

When the clutch member 149 descends, the spring 197^b returns the rod 197 to its normal position and thereby locks the clutch members 73 and 74.

When by the stoppage of the vehicle dur-

ing a break-down, the bevel pinion 117 is brought into engagement with the bevel teeth of the wheel 72, as has heretofore been explained, the said bevel pinion 117 will not be operated, because clutch members 73-74 will have been previously disengaged by the driver and said pinion 117 therefore cannot drive the fare indicator.

The resetting mechanism, whose function it is to restore to zero the trip distance indicator, the trip time indicator, the fare indicator and the indicator of extras, is arranged as follows:

The gear wheel 31 fixed to the shaft of the trip distance indicator and the gear wheel 35 fixed to the shaft of the trip time indicator are connected by an idler wheel 203.

The gear wheel 36 of the trip time indicator and the gear wheel 39 of the fare indicator are connected by an idler wheel 204.

The gear wheel 39 and the gear wheel 47 of the indicator of extras are connected by an idler wheel 205.

Upon the shaft 173 is loosely mounted a sleeve 206, one end of which carries a gear wheel 207 in mesh with the gear wheel 48 of the indicator of extras.

To the sleeve 206 are fixed two ratchet wheels 208, 208^a, while upon said sleeve are loosely mounted two gear wheels 209, 209^a, each adjacent to its respective ratchet wheel, and in mesh with the gear wheels 163 and 164, hereinbefore described in connection with the setting mechanism. These gear wheels carry spring pressed pawls 210 and 210^a, each arranged to engage its respective ratchet-wheel 208, 208^a.

Each pawl 210 and 210^a is provided with a tail arranged to strike a fixed abutment 211, 211^a, Fig. 11.

By this construction, when the setting mechanism is turned to set up a basic fare on the fare indicator, as fully explained hereinbefore, either the gear wheel 163 or the gear wheel 164 is rotated, according to whether the apparatus is being set for one or two passengers, or for three or four passengers, as will be understood from the description hereinbefore. Such rotation of either gear wheel 163 or 164 will cause a rotation of the corresponding gear wheel 209 or 209^a, which, however, will merely drag its respective pawl, 210 or 210^a around over the corresponding ratchet wheel 208 or 208^a, thus not moving the said ratchet wheel. When, however, the setting mechanism is turned back to zero, the gear wheel 163 or 164, which is at that time being rotated backward, will rotate the corresponding gear wheel 209 or 209^a in mesh with it, and the pawl 210 or 210^a respectively, or such backwardly rotating gear wheel will engage its respective ratchet wheel 208 or 208^a, and thus rotate the same and with it the sleeve

70

206, which also causes a rotation of the gear wheel 207, and the train of resetting gears connected with it, namely, 48, 47, 205, 39, 36, 35, 203 and 31, which results in a corresponding rotation of the shafts of the indicators which are to be reset, namely, the indicator of extras, the fare indicator, the trip time indicator and the trip distance indicator. The proportions of the gear wheels are such that the shafts of the said indicators may be given one complete revolution by the backward rotation of the gear wheel 207, so that no matter what the position of any counting wheel of any said indicators may be, it can be brought back to its zero position.

At this zero position the tail of the respective pawl 210 or 210^a strikes the corresponding abutment 211 or 211^a whereby the pawl is freed from the corresponding ratchet wheel 208 or 208^a so that the resetting train will always be stopped at the zero position of the indicators.

In addition to the various indicating devices hereinbefore described, the apparatus also comprises a recording mechanism, which will now be described.

At the upper end of the shaft 71, Figs. 1 and 4 is fixed a star wheel 214, Fig. 4, which engages the inner end of a lever 215 fulcrumed at 216, the outer end of which lever is provided with a pawl 217 engaging a ratchet wheel 218, the pawl being provided with an arm pressed by a spring 219 carried by the lever 215, as will be clear from Fig. 4.

The shaft 71 is continuously operated by the clock mechanism, through the bevel gears 69 and 70.

Hence the star wheel 214 will oscillate the lever 215 and thereby rotate the ratchet wheel 218 step by step, the lever 215 being moved by a spring 220, in opposition to the star wheel 214.

The ratchet wheel 218 is fixed on a short shaft or stud 221, journaled in a plate 222, the shaft having a square socket at its inner end.

Into this squared socket may be inserted the squared end of a driving shaft 223 Fig. 5 upon which is mounted a winding up drum 224, said shaft 223 being journaled in end plates 225, Figs. 3 and 5 of a recorder frame, which comprises, in addition to said end plates, suitable connecting plates, as for example the side plates 226 and 227, Fig. 5.

In this recorder frame are journaled a platen drum 228 and a supply drum 229. Upon the latter is mounted the roll of wide record paper, said paper being led over the platen drum 228 to the winding up drum 224.

The recorder frame, with its drums may be slid upward into the apparatus until the

squared end of the drum shaft 223 enters the socket in the lower end of the shaft 221. A spring catch 230 engaging the lower end plate retains the recorder frame in place. In order to make it easier to insert the recorder frame and insure the connection of the shafts 223 and 221, the upper end plate is provided with a pin 231, Fig. 3, which is arranged to enter a conical socket in the bearing plate 222 of the machine. 75

Upon the end of the star wheel shafts 22, 34, and 38, and upon the end of the shaft 25^c which carries the total indicator of extras are mounted heart cams, 232, 233, 234 and 235, each of which is engaged by one end of a recording lever, as indicated at 236, 237, 238 and 239, these levers being fulcrumed so as to swing in a vertical plane. 80

In addition to the recording levers 236, 237, 238 and 239, just described, three additional recording levers 240, 241, 242, Fig. 3, are provided, these also being fulcrumed so as to swing in a vertical plane. 85

The lever 242, is connected by a link 243 to a crank 244 on a rock shaft 245 journaled at the lower part of the apparatus and extending horizontally, as shown in Fig. 1. On the said shaft is fixed an arm 246 which extends upward between the two gear wheels 209 and 209^a each of said gear wheels being provided with a pin, as shown at 247 and 248, Figs. 1 and 25. 90

When the setting device is moved to set the apparatus for one or two passengers on a time basis, the gear wheel 209 is moved loosely on the sleeve 206, and its pin strikes the arm 246 and swings it so as to rock the shaft 245, which, by means of the crank 244 and the link 243 moves the recording arm 242 on its pivot in a vertical plane. 100

When the setting device is moved to set the apparatus for three or four passengers, the gear wheel 209^a is moved loosely on the sleeve 206 and its pin strikes the arm 246, and swings it so as to rock the shaft 245, 110 this moving the recording arm 242 on its pivot in a vertical plane. 105

As the gear wheels 209 and 209^a move to different extents, according as the respective disks 127 and 128 are turned to set up a basic time charge or a basic distance charge, so also the recording arm 242 is moved to different extents to record the character of the service rendered, that is, whether it is on a time basis or on a distance basis. 115

The recording arm 240 is fixed upon the end of the shaft 185, whose crank arm 184 is operated by the movement of the swinging indicator 167, as hereinbefore described. Consequently when said swinging indicator 167 is moved to indicate one or two passengers, it moves the recording arm 240 in one direction, and when said indicator is moved in the opposite direction to indicate three or four passengers, it moves the recording arm 120 125 130

240 in the opposite direction. When the indicator 167 is in its zero position, the recording arm 240 is horizontal.

The recording arm 241 is fixed on the end 5 of the shaft 202, which is rocked when the rod 197 is moved manually at the time of a break-down, to cut out the fare recorder. Consequently, the movement of this shaft 202 swings the recording arm 241 in a vertical plane.

10 Each of the recording arms 236 to 242 inclusive, is provided with a marking device, for example a stylus, one of which is shown at 249 in Figs. 4 and 5.

15 Each stylus bears on the paper web at the place where it passes over the platen roller 228. By making each stylus of suitable material, for example, brass, and providing the paper with a suitably prepared surface, as 20 is well known in the art, each stylus will make a mark on the paper when the same is traveling over the platen roller 228 under the action of the winding-up roller 224 driven by the clock work.

25 In order to permit the recording arms to be lifted from the framework with its attached rollers, and for the purpose of holding said arms in yielding contact with the paper, they are made resilient, that is to say, 30 like light plate springs at their rear ends.

For the purpose of lifting simultaneously all said arms from the paper, a rod 250 extends vertically alongside said arms as shown in Fig. 3 this rod being provided 35 with a plurality of projections one adjacent to each arm, said projections being indicated at 251.

When the rod 250 is rotated on its axis, 40 said projections will force said recorder arms outward and thus lift their marking devices from the paper.

In order to rotate said rod 250 conveniently, the lower end of said rod is squared as indicated in Figs. 3 and 5, and upon the 45 squared end is secured a door or lid 252, Fig. 9 which is arranged to cover the lower end of the recorder apparatus. When it is desired to remove the recording mechanism in order to obtain the completed record, and 50 to insert a blank record, the door is swung to one side, thus turning the rod 250 and lifting the recorder arms from the paper, whereupon the catch 230 is released and the framework with its contained mechanism is 55 drawn downward. When the frame work is pushed upward into place the catch 230 springs into place and the door may then be swung into place, thus rotating the rod 250 in the direction to swing the projections 60 251 out of contact with the recorder arms which spring back against the paper.

In Fig. 23 is illustrated a part of a record sheet, such as would be produced by the apparatus under some circumstances.

65 In order to indicate the total distance

traveled by the vehicle, the apparatus may be provided with a suitable total distance indicator as indicated at 253, Fig. 1.

This is shown, in the present example, as an ordinary Veeder ratchet counter, the construction of which is well known to those skilled in the art, and hence requires no particular description herein. This counter has its ratchet arm 254 operated by a bell crank (not shown), which is oscillated by a lug 75 255 on the upper surface of ratchet 59.

It is to be understood that the apparatus hereinbefore described is inclosed in a suitable casing.

The external appearance of the apparatus 80 will be clear from Figs. 6, 7 and 8. The casing is secured to the vehicle in any suitable way, and the drive shaft 64 is arranged to be driven from the vehicle wheel by any suitable means, as for example the usual 85 flexible shaft.

These features are not illustrated herein as they constitute no part of the present invention.

What I claim is:

1. The combination, with a trip-distance indicator, and means actuated by the movement of the vehicle for driving said trip-distance indicator, of a fare indicator, and means actuated by the trip-distance indicator and arranged to couple the fare indicator to said driving means.

2. The combination, with a trip-distance indicator, and means actuated by the movement of the vehicle for driving said trip-distance indicator, of a fare indicator, a setting device arranged to set up a basic fare on the fare indicator, and means actuated by the trip-distance indicator and arranged to couple the fare indicator to the means for driving said trip-distance indicator.

3. The combination, with a trip-distance indicator, and means actuated by the movement of the vehicle for driving said trip-distance indicator, said driving means including a clutch mechanism, of a fare indicator, a setting device arranged to set up a fare on the fare indicator and lock the clutch mechanism, and means actuated by the trip-distance indicator after the locking of the 110 said clutch mechanism, and arranged to couple the fare indicator to the means for driving the said trip-distance indicator.

4. The combination, with a trip-time indicator, and clock mechanism arranged to actuate said trip-time indicator, of a fare indicator, and means actuated by the trip-time indicator and arranged to couple the fare indicator to said clock mechanism.

5. The combination, with a trip-time indicator, and a clock mechanism arranged to actuate said trip-time indicator, of a fare indicator, a setting device arranged to set up a fare on the fare indicator and connect the trip-time indicator to the clock mecha- 125 130

nism, and means actuated by the trip-time indicator and arranged to couple the fare indicator to the clock mechanism.

6. The combination, with a trip-distance indicator, a trip-time indicator, and means actuated by the movement of the vehicle for driving the trip-distance indicator, said means including a clutch mechanism, of a clock mechanism, a fare indicator, and a 10 setting device arranged to set up a fare on the fare indicator, to lock the clutch mechanism and to couple the trip-time indicator to the clock mechanism.

7. The combination, with a trip-distance indicator, a trip-time indicator, and means actuated by the movement of the vehicle for driving the trip-distance indicator, of a clock mechanism, a fare indicator, a setting device arranged to set up a fare on the fare 15 indicator, to couple the trip-distance indicator to its driving mechanism and to couple the trip-time indicator to the clock mechanism, means actuated by the trip-distance indicator for coupling its driving mechanism with the fare indicator, and means actuated by the trip-time indicator for coupling the fare indicator with the clock mechanism.

8. The combination, with a trip-distance indicator, a trip-time indicator, and means actuated by the movement of the vehicle for driving the trip-distance indicator, said means including a clutch mechanism, of a clock mechanism, a fare indicator, a setting 30 device arranged to set up a fare on the fare indicator, to lock the clutch mechanism and to couple the trip-time indicator to the clock mechanism, means actuated by the trip-distance indicator for coupling the driving 35 means with the fare indicator, and means actuated by the trip-time indicator for coupling the fare indicator with the clock mechanism.

9. The combination, with a fare indicator, a clock mechanism, and operating means actuated by the movement of the vehicle for operating the fare indicator, of a reciprocating member actuated in one direction by the said operating means, a delay-action device 45 for delaying the movement of the reciprocating member in the other direction, and means for coupling the fare indicator to the clock mechanism, said means being arranged to be thrown into action upon the 50 completion of the delayed movement of the reciprocating member.

10. The combination, with a fare indicator, a clock mechanism, and operating means actuated by the movement of the vehicle for driving the fare indicator, of means for 60 coupling the fare indicator to the clock mechanism, a spring tending to force said coupling means into its operating position, a reciprocating member arranged to be moved in one direction by the operating means 65 which drives the fare indicator, and to be driven in the opposite direction by the said coupling means, and a delay action device for delaying the last-mentioned movement.

11. The combination, with two indicators 70 arranged side by side, each comprising a plurality of counting wheels, of an oscillatory device arranged between the two indicators, said oscillatory device being arranged to actuate the nearest counting wheel 75 of one indicator and the most remote counting wheel of the other indicator, and means for oscillating said oscillatory device.

12. The combination, with an indicator and an oscillatory device for actuating said 80 indicator, of a rotary shaft, means operated by said shaft for actuating the oscillatory device, and a recording mechanism having a recording arm, and means operated by the rotary shaft for oscillating said recording 85 arm.

13. The combination, with an indicator having a plurality of counting wheels, of a shaft to which one of said counting wheels is fixed and on which the others are loosely 90 mounted, means for actuating the counting wheels, whereby the shaft is rotated, a recording device having a recording arm, and means operated by said shaft for actuating the recording arm.

14. The combination, with a charge indicator, and means for actuating said charge indicator, of a setting indicator, setting means for setting the charge indicator and simultaneously actuating the setting indicator, a 100 recording device having recording arms, means controlled by the setting means for operating one recording arm, and mechanism controlled by the means for actuating the charge indicator for operating another 105 recorder arm.

In witness whereof I have hereunto affixed my hand this 16th day of June, 1911.

GEORGE S. MAXWELL.
